CLAIM

The ornamental design for a drawer side panel, as shown and described.

DESCRIPTION

FIG. 1 is a perspective view of a drawer side panel showing my present design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is an enlarged fragmentary view of left side of the perspective view of FIG. 1; and,

FIG. 9 is an enlarged detailed view of the encircled area 9 in FIG. 8.

All broken line portions of the figure drawings are included to show portions of the article that form no part of the claimed design.
